UNITED STATES PATENT OFFICE.

ERNEST OLDENBUSCH, OF BROOKLYN, NEW YORK.

ASH-TRAY AND CIGAR-REST.

1,212,995.

Specification of Letters Patent. Patented Jan. 16, 1917.

Application filed January 26, 1916. Serial No. 74,316.

To all whom it may concern:

Be it known that I, ERNEST OLDENBUSCH, a citizen of the United States, and a resident of the city of New York, borough of Brooklyn, in the county of Kings and State of New York, have invented a new and Improved Ash-Tray and Cigar-Rest, of which the following is a full, clear, and exact description:

10 This invention relates to ash trays and supports for cigars, and has for an object the provision of an improved simple arrangement whereby the ashes from a cigar may be readily dropped into a preliminary receptacle as the cigar is supported on the rest.

Another object in view is to provide a construction which includes a box or container and a pair of tiltable members acting 20 together, the tiltable members acting as a combined rest and preliminary container for the ashes which may be readily discharged into the box at any time.

In the accompanying drawings: Figure 1 is a perspective view of a device embodying the invention. Fig. 2 is a side view of the device with the moving parts in their elevated or discharging position. Fig. 3 is an end view of the construction shown in Fig. 2, the moving parts being shown open in dotted lines. Fig. 4 is a sectional view through Fig. 1 on line 4—4, the moving parts being shown in their discharging position in dotted lines. Fig. 5 is a detail 35 fragmentary sectional view through Fig. 4 on line 5—5.

Referring to the accompanying drawings by numerals, 1 indicates a box or container for receiving and storing the ashes until the same may be cleaned. Box 1 is provided with a lid 2 connected therewith by a suitable hinge 3 whereby the box may be opened and closed whenever desired. The lid 2 is provided with an opening 4 for accommodating the pivotally mounted members 5 and 6 which present a preliminary or first receptacle for receiving the ashes from cigars and the like. Each of these members merge into an extension 7 having sides 8 whereby a rest is provided. In forming the

members 5 and 6 bottoms 9 and 10 are provided which merge into sides 11, 12, 13 and 14. The sides 11 and 14, for instance, are provided with a plurality of gear teeth 15 and 16, respectively, and straight portions 55 17 and 18, respectively, said straight portions meeting when the parts are in the operative position, as shown in Fig. 1, and the toothed portions operating when either of the members 5 or 6 is moved from the position shown in Fig. 1 to the position shown in Fig. 4. By providing this form of gearing a simple strong construction is produced and yet both members 5 and 6 are dumped when either member is actuated. These 65 members may be operated by grasping either of the extensions 7 and moving the same, or handle 19 may be actuated. The sides 12 and 13 are constructed similar to the sides 11 and 14 so that the movement 70 of members 5 and 6 will be uniform. In forming the lid 2 a pin 20 is provided for each of the side members 11 to 15, inclusive, the pins being arranged in proper relationship with the teeth 15 and 16, respectively, 75 to allow a proper hinge movement of members 5 and 6.

In operation the device is arranged as shown in Fig. 1 and member 7 used as a rest. The ashes from a cigar, cigarette or the like may be easily dumped into the preliminary receptacle provided by members 5 and 6. After some appreciable amount of ashes has accumulated the same may be readily dumped into the box 1 so that the 85 device will look perfectly clean and sanitary. It is of course evident that the members 5 and 6 may be dumped at any time in order to maintain the same clean and free from ashes.

90 What I claim is:—

In a device of the character described, a box or container having a lid provided with an aperture, and a preliminary ash tray arranged so as to fill said aperture when in 95 operative position, said ash tray comprising a pair of bottom members contacting at their adjacent edges and a pair of upstanding sides having interlocking geared portions so that when one bottom is raised the 100

other will also be raised, each of said bottoms having a horizontal extension projecting beyond said box and acting in the double capacity of a cigar rest and as a handle for moving the preliminary tray.

In testimony whereof I have signed my

name to this specification in the presence of two subscribing witnesses.

ERNEST OLDENBUSCH.
